John L. Drake

UNITED STATES PATENT OFFICE.

JOHN L. DRAKE, OF CINCINNATI, OHIO.

LAMP.

Specification of Letters Patent No. 25,493, dated September 20, 1859.

To all whom it may concern:

Be it known that I, JOHN L. DRAKE, of Cincinnati, in the county of Hamilton and State of Ohio, have invented a new and Improved Lamp; and I do hereby declare that the following is a full, clear, and exact description of the same, reference being had to the annexed drawings, making a part of this specification, in which—

10 Figure 1, is a vertical central section of my invention. Fig. 2, is a detached external view of a portion of ditto. Fig. 3, is a plan or top view of the cap and chimney holder of ditto. Fig. 4, is a plan or top 15 view of the part shown in Fig. 2.

Similar letters of reference indicate corresponding parts in the several figures. This invention relates to an improvement in that class of lamps that are designed for 20 burning for illuminating purposes, coal oils, of the heavier grades and other hydro-carbons which require a considerable amount of oxygen to support a proper combustion.

The object of the within described invention is to make suitable provisions, whereby the flame may be supplied with a requisite amount of warm oxygen to feed the flame and at the same time the top or cap be kept in a sufficiently cool state to 25 permit the same to be detached by the fingers for the purpose of trimming the wick or supplying the font with oil.

To enable those skilled in the art to fully understand and construct my invention I 30 will proceed to describe it.

A, represents the body of the lamp top. This body is of cylindrical form and is struck up or swaged in suitable form from 35 metallic plate. The lower end of the body A, has a screw thread *a*, cut on it and the body A, above the screw *a*, is perforated as shown at *b*. In the upper part of the body A, a horizontal flanch *c*, is placed, and attached to the body, said flanch having a circular opening *d*, through which the wick tube B, passes, the lower end of the wick tube being attached to the bottom of the body A.

The wick tube B, extends some distance 40 above the body A, and is constructed with a view of retaining a plurality of wicks for the purpose of augmenting capillarity and thereby insuring a full supply of oil to the flame. This wick tube does not in this place 45 require a detailed description as it was patented by me May 17th 1859, and besides an

ordinary wick tube may be used with the parts comprising this invention.

On the upper part of the body A, at two opposite points of its periphery there are 50 projections *e*, *e*, the use of which will be presently shown.

C, represents a cap which is of the usual dome-shape and D, is the chimney holder which is of annular dish-form encompassing the lower part of the cap. The cap and holder are struck up or swaged from a single piece of metal plate. The top of the cap is slotted as usual as shown at *f*, and the chimney holder D, is perforated near 55 the base of the cap as shown at *g*, see Figs. 1 and 3. The lower part of the cap C, at its junction with the chimney holder D, has right angular slots *h*, made in it at 60 opposite points of its periphery and the cap C, and holder D, are secured to the body A, in consequence of the projections *e*, *e*, fitting in the slots *h*, see more particularly Fig. 1.

On the wick tube B, a circular disk E, is placed. This disk is some distance below 65 the top of the cap C, and does not touch its sides, a space *i*, being allowed all around the disk between it and the cap to permit air to ascend to the flame. The disk E, need not 70 be permanently attached to the wick tube 75 but fitted snugly on it so that it may be readily removed when necessary.

In the body A, of the lamp top a shaft *j*, is placed horizontally, said shaft having a thumb wheel *k*, on one end and small 80 toothed wheels *l*, *l*, near its opposite end. The wheels *l*, *l*, bear against the wick and raise and lower it as may be required by 85 turning the shaft.

The operation is as follows: The flame 90 is supplied with two currents of air, one passing through the perforations *b*, up into the cap C, and being spread by the disk E, strikes against the interior of the cap C, and is deflected from thence so as to impinge against the flame at its base. The other current passes through the perforations 95 *g*, and up between the glass chimney and the cap C, and impinges against the sides 100 of the flame. The disk E, causes the current of air in the cap to strike against the base of the flame in a thin sheet which becomes readily warm in consequence of being extended or spread out, and the disk also by thus spreading the current insures a 105 more uniform supply to the flame, the current not being liable to the fluctuations of 110

one that is unimpeded in its course. In this latter respect the effect is quite similar to that produced by wire gauze or a perforated division plate which have been used for such purposes, although applied in a different way from that herein shown and of course without the important feature of alternating or spreading out the current of air in its passage to the flame. By having the 5 holder D, perforated at the base of the cap and the holder and cap connected and arranged as shown a large supply of air is admitted to the flame at its outer sides and the exterior of the holder is kept in a cool 10 state so that the fingers may be applied to it and the top unscrewed from the font while the lamp is burning. This is an important feature of the invention for in all 15 lamps for similar purposes that have passed under my observation, a considerable 20

time must elapse for the lamp to cool after the wick is extinguished in order that the top or cap may be unscrewed.

I do not claim broadly the employment of two currents of air to feed the flame, one 25 impinging against its base and the other against its sides. Neither do I claim a perforated chamber at the base of the lamp top; but,

I do claim as new and desire to secure 30 by Letters Patent,

The employment or use of the disk E, applied to the wick tube B, and used in connection with the cap C, and arranged relatively with it for the purpose set forth.

JOHN L. DRAKE.
